UNITED STATES PATENT OFFICE.

NICHOLAS J. LUTTRELL, OF LIVERPOOL, NEW YORK.

ELECTROTHERMOSTATIC SWITCH.

Application filed December 24, 1925. Serial No. 77,491.

This invention relates to a thermally controlled electric switch adapted to be closed at will and to be automatically opened by heat developed in an electrical resistance 5 associated with a thermostatic bar and forming a part of electric switch or automatic circuit breaker.

The main object is to provide a compact and comparatively inexpensive switch of this 10 character having a wide range of uses in which the heating of the electrical resistance for opening the switch may be attributable to different causes but will have the same effect and still serve different purposes.

15 The specific object is to make a switch of this type from two spring terminals having cooperative contacts and arranged in such manner that the one terminal is pressed into contact with the other for closing the 20 circuit, both contacts will be moved in the same direction but in intersecting arcs and when the pressure is released the contacts will automatically interlock with each other to hold the circuit closed.

25 Another specific object is to provide one of these terminals with a thermostatic bar and an electric resistance coil, both connected in series with the secondary switch terminal in such manner as to form an electric switch 30 in which the heat developed in said resistance will cause a deflection of the thermostatic bar and secondary switch terminal sufficient to release it from interlocking engagement with the primary terminal and thereby to automatically open the switch 35 for breaking the circuit.

Other objects and uses relating to specific parts of the device will be brought out in the following description.

40 In the drawings:

Figure 1 is an enlarged longitudinal sectional view of a double switch adapted to be used for controlling directional signals of automobiles and other vehicles.

45 Figure 2 is a diagrammatic view of the same switch and lighting circuits for directional signals.

50 Figure 3 is a diagrammatic view of a single thermally controlled electric switch connected in a motor circuit and adapted to be automatically opened (after being closed manually) by heat developed in the resistance due to overload upon the circuit.

55 Figure 4 is a diagrammatic view of a single switch as used in the charging circuit

of a storage battery for preventing overloading of the battery.

The double thermostatic switch shown in Figures 1 and 2 is adapted to be used for controlling the circuits to a pair of incandescent electric lamps, —L— and —R— or other electrically operated translating devices which are connected in branch circuits —a— and —a'— of a main circuit —A— deriving current from a source of electric 65 energy as a battery —B—.

This double switch comprises a pair of flat spring terminals —1— and —1'—, an additional pair of flat spring terminals —2— 70 —2'—, a pair of thermostatic bars —3— and —3'— and electric resistance coils —4— and —4'—, the terminals of each pair being secured at one end to an insulating support —5— so as to extend in opposite directions therefrom and normally in spaced 75 parallel planes under their own tension.

The free ends of the terminals at either side of their insulating support —5— cooperate to open and close the circuit through its corresponding signal independently of the other set of terminals and constitute cooperative contacts —6— and —7— and —6'— and —7'— slightly varying distances from their insulating support —5— so that they may be sprung or deflected under pressure relatively to said support for closing the circuits through their respective signals —R— and —L—.

The spring terminals —1— and —1'— are preferably formed in one piece secured 90 midway between its ends to the insulating support —5— for economy and compactness, the central portion thereof being connected to one side of the battery —B— for supplying current to both switches. 95

The contact members —7— and —7'— are offset toward their companion contact members —6— and —6'— to form shoulders with which their companion contact members —6— and —6'— are adapted to engage when 100 depressed for closing the circuit through the corresponding translating devices.

The inner ends of the spring terminals —2— and —2'— are secured in insulated relation to the support —5— to extend laterally in opposite directions therefrom and in spaced parallel relation to the corresponding terminals —1— and —1'— so as to permit their respective contact members —7— to yield when the free ends of the adjacent 110

terminals —1— and —1'— are pressed against them.

It is now evident that the free ends of both sets of terminals may be deflected from their normal positions by pressure upon the free ends of the terminals —1— and —1'— and by contact of those terminals with the free ends of the terminals —2— and —2'— thereby causing the contact members of either set to move in different intersecting arcs as *a—a* and *b—b* respectively, Figure 1.

The contact members —6— and —6'— normally project slightly beyond their companion contact members —7— and —7'— so that when depressed toward their respective terminals —2— and —2'— they will first engage the adjacent faces of their corresponding shoulders —7— and —7'— and, as the pressure is continued the terminals —2— and —2'— will be also deflected in the same direction until the edges of the companion contact members reach the intersection of their respective arcs of movement *a—a* and *b—b* whereupon the end faces of said contact members will snap into engagement with each other and will be held in such engagement by the tension of their respective terminals tending to return to their normal positions until released in a manner presently described.

This release may be effected manually by simply depressing the free ends of the terminals —2— and —2'— when interlocked with the free ends of their adjacent terminals —1— and —1'— and for this purpose the free ends of the terminals —2— and —2'— are provided with extension finger pieces —8— and —8'— projecting beyond the contact members —6— and —6'— of the adjacent terminals —1— and —1'— as shown in Figure 1.

Or, as shown in Figure 2, these extensions —8— and —8'— may be omitted and the free ends of the members —1— and —1'— depressed into locking engagement with the parts —7— and —7'— by push buttons —9— and —9'—.

This release of the interlocked contact members —6— and —7— or —6'— and —7'— may also be effected automatically by heat developed in the corresponding coils —4— or —4'— which are wound upon the thermostatic bars —3— and —3'— respectively and are electrically connected in series with their respective signals —R— and —L— and corresponding switch terminals —2— and —2'—.

These thermostatic bars —3— and —3'— are preferably made of electric conducting spring leaves of different coefficients of expansion and have their inner ends secured to the inner ends of their respective switch terminals —2— and —2'— for electrical connection therewith, the outer ends of said thermostatic bars being arranged to engage

the inner faces of suitable ledges —10— and —10'— on the free ends of the terminals —2— and —2'—.

These thermostatic bars —3— and —3'— are arranged so that their free ends will be deflected against their respective ledges —10— and —10'— when subjected to heat under a predetermined temperature for automatically opening either switch after being closed in the manner described.

The resistance coils —4— and —4'— are electrically connected at one end to their respective thermostatic bars —3— and —3'— and have their other ends electrically connected to their corresponding signals —R— and —L—, said resistance coils being constructed and arranged so that when either switch is closed and held in its closed position in the manner previously explained for an approximately predetermined interval of time the corresponding coil will become heated to such an extent as to deflect its thermostatic bar against the adjacent ledge as —10— or —10'— thereby effecting a corresponding deflection of the corresponding contact member —7— or —7'— sufficiently to disengage it from its companion contact member as —6— or —6'— and thereby to permit the automatic separation and opening of the companion members of the switch for breaking the circuit.

Under these conditions it is evident that when either switch is closed manually in the manner described it will remain closed until sufficient heat is developed in the corresponding coil to cause its thermostatic bar to automatically release the switch terminals from interlocking engagement with each other and permit the automatic opening of the switch.

For example, if it is desired to energize the signal —R— to indicate a right hand turn the free end of the terminal —1— will be depressed by the push button —9— sufficiently to cause interlocking engagement between the contact members —6— and —7— which will close the circuit through the resistance coil —4—.

The contact members —6— and —7— will be automatically held closed in the manner described thereby maintaining a closed circuit through the coil —4— for an appreciable interval of time according to the construction and arrangement of the coil or until the thermostatic bar —3— has been heated and deflected sufficiently to release the switch terminals from said interlocking engagement whereupon the terminals will open under their own tension to break the circuit thereby relieving the operator from the necessity of opening the circuit manually after the period required for the energizing of the signal.

In like manner the other switch may be closed and released for energizing and de-

energizing its corresponding signal —L—.

In Figure 3 is shown a single switch for automatically breaking a motor circuit in case of an overload thereof.

- 5 The motor as —M— may be connected to any source of electric energy for supplying current thereto through the medium of wires —W—, said circuit including therein one of the electric switches, previously described, including the heater coil —4— and thermostatic bar —3—, the coil —4— being connected in series between the motor —M— and switch terminal —2—.

Otherwise the construction of the switch 15 is substantially the same as that previously described except that the terminal —2— is provided with an extension —8— for engagement by a push button —9— for releasing said terminal from engagement 20 with the terminal —1— while the other terminal is engaged by a similar push button —9— for closing and locking the switch.

In Figure 4 is shown a similar switch 25 connected in the charging circuit —C— for a storage battery —B'— and adapted to be operated in a manner similar to either of the switches shown in Figure 2 except that in case of overload of the battery the 30 heat developed in the coil —4— will automatically release the interlocking terminals from their closed position and allow them to open for breaking the circuit.

The operation of the switch, in so far as 35 it relates to the locking engagement of the terminals by pressure of one against the other for closing the circuit and the automatic release of the terminals from engagement one with the other through the heating of the coil —4— and consequent deflection of the thermostatic bar —3— for opening the switch, is substantially the same in the several uses described, the only difference being in the circuits in which 40 the switch is connected according to the different uses.

What I claim is:

1. An electric switch comprising two flat spring terminals normally supported at one

end in parallel spaced relation and having their other ends extending in the same 50 direction and free to yield transversely under pressure of one against the other in the same direction, one of said terminals having a shoulder offset toward the other terminal, the end of said other terminal 55 being extended slightly beyond the shoulder to abut against said shoulder and thereby to automatically hold the terminals in electrical contact when the pressure is released.

2. An electric switch comprising a primary spring terminal and a secondary spring terminal, both of said terminals being supported at one end in normally spaced parallel relation and insulated one from the other and having their other ends 60 free to yield transversely under pressure, the free end of the secondary terminal being provided with a shoulder offset toward the end of the primary terminal, said primary terminal being extended slightly 65 beyond the shoulder whereby deflection of the free ends of both terminals in one and the same direction by pressure of the primary terminal against the secondary terminal will cause the end of the primary terminal to abut endwise against the shoulder of the secondary terminal for holding 70 the terminals in electrical contact when the pressure is relieved.

3. An electric switch as in claim 2 having 75 heat controlled means operable under a predetermined temperature for causing the release of the engagement of one terminal with the other.

4. An electric switch as in claim 2 in which a thermostatic bar is operatively 80 connected to the secondary terminal for automatically withdrawing the same from engagement with the primary terminal when subjected to heat under a predetermined temperature, and an electric heater 85 connected in the switch circuit adjacent said thermostatic bar for heating the same.

In witness whereof I have hereunto set my hand this 21st day of December, 1925.

NICHOLAS J. LUTTRELL.
